FLASH-LIGHT.

1,308,032.

Specification of Letters Patent.

Patented July 1, 1919.

Original application filed February 7, 1914, Serial No. 817,090. Divided and this application filed January 19, 1918. Serial No. 212,582.

To all whom it may concern:

Be it known that I, BERNARD BENEDICT, a citizen of the United States, residing at New York city, in the county of Bronx, 5 State of New York, have invented certain new and useful Improvements in Flash-Lights, of which the following is a specification, reference being had therein to the accompanying drawings, forming part thereof.

- 10 My invention relates to portable electric lights and pertains more particularly to a flashlight intended to be carried in the upper vest pocket in the same manner that a fountain pen is carried therein, and my 15 present invention is a divisional part of the subject matter of my application for patent for a flashlight filed February 7, 1914, Serial No. 817,090. A fountain pen is ordinarily provided with a spring clip or member 20 adapted when the pen is placed in the upper vest pocket to embrace between itself and the side of the pen the thickness of the material of the vest at the outer side of said pocket, the pen being thereby held securely. 25 I utilize the same principle for holding the flashlight of my invention in the pocket, and the spring clip instead of being merely a clip for securing the flashlight is further utilized as a means for maintaining the 30 circuit through the lamp and battery in open condition while the flashlight is in the pocket and for conveniently enabling the making or closing of the circuit when the flashlight is not in the pocket and it is desired that the lamp shall be lighted.

In carrying out my invention, therefore, in the embodiment thereof illustrated in the accompanying drawings, I construct the barrel or exterior casing of the flashlight 40 to resemble in appearance a fountain pen, and upon the exterior of this outer shell or casing I secure a spring clip preferably imitating as far as may be the spring clip on the side of the barrel of a fountain pen, 45 and in respect to the circuit-closing means, I utilize this spring clip as sliding means for making the circuit and allowing the same to remain closed until, by the pressure of the finger or thumb, the spring clip or circuit-closing device is moved to its initial normal 50 position breaking the circuit. The interior

of the shell or casing of the flashlight will be provided with a suitable battery and at one end of said casing will be supplied the customary reflector and electric lamp, and 55 the exterior spring clip or circuit-closing device will normally be out of a position closing the circuit and therefore holding it open or broken, and said spring clip when the flashlight is inserted in the pocket will pass 60 to the outer side of the material of the vest at the pocket and be thereby prevented from closing the circuit and wasting the battery, this being by reason of the fact that the upper front edge of the vest pocket will engage or press against and beneath the circuit-controlling slide which carries the 65 pocket-engaging spring clip and will prevent this slide from moving to the circuit-closing position.

The invention will be fully understood from the detailed description hereinafter presented, reference being had to the accompanying drawings, in which:

Figure 1 is a front elevation of a flashlight embodying my invention;

Fig. 2 is an enlarged central longitudinal section on a vertical plane indicated by the line 2—2 of Fig. 1 as viewed from the left;

Fig. 3 is an end view as seen from below 80 in Fig. 2 with the lamp and the reflector removed or omitted;

Fig. 4 is an elevation of the reflector as viewed from the side in Fig. 2;

Fig. 5 is a partial central longitudinal section on a vertical plane indicated by the line 5—5 of Fig. 2 as viewed from the left 85 and with parts omitted; and

Fig. 6 is a transverse section on a horizontal plane indicated by the line 6—6 of Fig. 2 90 as viewed from above, but rotated ninety degrees, corresponding to Fig. 5.

In the pocket electric light embodying my invention illustrated in the accompanying drawings, the exterior shell or casing is of 95 metal, and this shell or casing is of elongated form and meant to imitate as far as convenient the appearance of a fountain pen. This casing is shown in the drawings as made up of a lower cylindrical section or part 1 and 100 an upper cylindrical cap part 2 fitting over the upper end of the lower casing part 1, the

cap part 2 being closed at its upper end. At its lower end the lower casing part 1 carries a reflector 3 having formed thereon a screw-threaded lamp socket 4 into which screws 5 the base 5 of a usual miniature incandescent lamp having its central terminal 6 exposed within the casing tube 1 and having its bulb 7 exposed at the outer end of this casing tube. The reflector 3 is shown as provided 10 with an edge flange 8 which engages the lower end of the casing tube 1, and at opposite sides thereof the reflector 3 is provided with outwardly indented laterally projecting studs 9 to enter into engagement with 15 angular grooves 10 formed in the inner wall of the outer end of the lower casing part 1, the studs 9 and grooves 10 forming what is commonly called a bayonet joint, by which the reflector 3 is detachably connected to the 20 lower end of the casing tube 1 in a manner that is well understood. The outer edge of the flange 8 serves as a convenient means for turning the reflector 3 both in connecting it with the end of the casing tube 1 and removing it therefrom when desired.

Within the tubular casing made up of the joined lower and upper parts 1 and 2, there is contained a suitable battery shown as comprising two cells placed in end-to-end relation, each of these cells having a zinc terminal 11 in the form of a cup and a central carbon terminal 12. These battery cells have a sheet 13 of celluloid or other suitable non-conducting material wrapped about them 35 for insulating their zinc terminals or cups 11 from the metallic casing parts 1 and 2, and the battery cells together with the non-conducting sheet 13 fit snugly within the lower casing tube 1 and project upward into 40 the larger upper casing tube or cap 2. The carbon terminal 12 of the lower battery cell is in contact with the central terminal 6 of the lamp. Means involving my invention and now to be described are provided for 45 maintaining the carbon terminal 12 of the lower battery cell in engagement with the central terminal 6 of the lamp and for completing and controlling the circuit of the battery through the lamp.

50 A non-conductive disk 14 forming a thrust block is fixed within the upper part of the casing cap 2, and a coiled thrust spring 15 is interposed between the upper end of the upper battery cell, in electrical 55 engagement with the zinc terminal 11 thereon, and the non-conductive disk or thrust block 14, to which the spring 15 is secured and is shown as having an upwardly projecting end part 16 which passes centrally 60 through the insulating block 14 and is riveted or upset at the upper side thereof, as appears in the drawings, particularly in Fig. 2 thereof.

65 A circuit-controlling slide shown as a transversely curved ribbed plate 17 is longitudinally slidable upon the upper end of the upper handle-providing casing part 2 upon which it is mounted for longitudinal sliding movement by means of inturned lugs 18 which pass through longitudinal slots 19 70 in the upper casing part 2 and are clenched or turned over toward each other at the inside thereof, grooves 20 being provided in the insulating disk or block 14 for the reception of the securing lugs 18, as appears 75 in the drawings, particularly in Fig. 6. The longitudinally sliding circuit-controlling plate 17 is provided with an electrically conductive circuit-controlling member shown as a pin or stud 21 having a head at the outside 80 of and extending through the plate 17 and projecting at the inside of the upper casing part 2 through a slot 22 provided in the upper casing part 2 and into a groove 23 provided longitudinally in the edge of the non-conductive abutment block or disk 14, as clearly appears in the drawings. It is to be noted that the uppermost and larger coil of the coiled thrust spring 15 lies in the path of the inner end part of the conductive 85 stud or contact pin 21 as this pin moves downward in the slot 22 for thereby closing the circuit when the circuit-closing slide 17 is moved downward, as will be readily understood and as clearly appears in the drawings, particularly in Fig. 2 thereof.

The circuit-controlling slide or slidable circuit-controlling plate 17 is provided with a downwardly projecting resilient clip 24 forming a hook for supporting the light and 100 shown as formed integral or in one piece therewith and as joined thereto by means of an offset or shoulder 25, and at its lower free end the resilient clip 24 is provided with a spherical end or ball 26. The resilient clip 24 is adapted to releasably engage a part of the apparel for supporting the light thereon and is adapted to receive between itself and the adjacent casing part 2, the material at the front of a pocket in which 105 the light may be carried for thereby retaining the light in the pocket, and in this connection the terminal ball 26 assists both in the entering of the edge of the pocket beneath the spring clip 24 and also in more 110 securely holding the light in place and from dropping out of the pocket, as will be readily understood.

It should be noted that the above described construction provides for the location of the 120 slidable circuit-controlling clip-carrying plate 17 at the upper or outer end of the upper or outer casing part 2, and that the resilient pocket-engaging clip carried by the circuit-controlling slide 17 projects toward 125 the lower or lamp-carrying end of the lower casing tube 1, thereby providing for a convenient circuit-controlling arrangement of the parts, providing for the arrangement of a plurality of end-to-end battery cells with- 130

in the casing, providing for conveniently holding the casing by its outer end part 2 in operating the circuit-controlling slide 17, providing for the housing or concealment 5 of the exposed bulb 7 of the lamp within the pocket, and also effectively providing a pocket light which closely resembles a usual fountain pen.

The pocket electric light embodying my 10 invention illustrated in the accompanying drawings is meant to be carried in the upper vest pocket or in some pocket of the clothing of the user, and it is of the greatest importance therefore that the clip-carrying circuit-controlling slide 17 shall be assured 15 against accidental movement which would complete or close the circuit of the battery through the casing and lamp. Therefore, in carrying out my invention it is intended that 20 the lower or lamp end of the pocket electric light illustrated in the drawings shall not reach, or shall only reach, the bottom of the pocket and that the upper front edge of the vest pocket will come in contact with the 25 shoulder or offset 25 provided on the spring clip 24, adjacent to the slidable circuit-controlling plate 17, so that the weight of the device thus resting upon the edge of the pocket at the shoulder 25 will keep the plate 30 17 from sliding downward or being accidentally pushed downward to a sufficient extent for the contact pin 21 to engage or come in contact with the spring 15, so that the circuit is maintained in the open condition 35 by reason of the engagement, as above described, of the device with the pocket in which it is carried.

The pocket electric light of my invention has been so constructed and designed that it 40 may be just as conveniently carried in the pocket of a vest as a fountain pen, and this is not only of importance in respect to the facility of carrying the light but also, because of this universal method of carrying fountain pens, the same habit already acquired may be further conveniently utilized. The pocket electric light of my invention is therefore intended to be carried in the same way that a fountain pen has heretofore been 45 50 carried by the user thereof and to occupy a position in the upper vest pocket alongside of the fountain pen.

It is obvious that various modifications may be made in the construction shown in 55 the drawings and above particularly described within the principle and scope of my invention.

I claim:

1. A pocket electric light comprising an 60 elongated casing having at one end a lamp and containing a battery for the lamp, and means for retaining the light on the apparel and closing the circuit comprising an elongated clip mounted for slidable circuit-controlling movement upon the side of the cas- 65

ing at the end of the casing opposite to the lamp and slidable longitudinally of the casing for controlling the circuit of the lamp and projecting toward the lamp-carrying end thereof, said clip being adapted to receive between itself and the casing the material of the apparel upon which the light may be carried. 70

2. A pocket flashlight comprising a conducting casing having at one end a lamp 75 with one of its terminals connected to the casing and the casing containing a battery having one of its terminals connected to the other terminal of the lamp, a covering of non-conducting material for insulating the battery from the casing, and means for retaining the flashlight on the apparel and closing the circuit comprising a slidable resilient clip mounted for slidable circuit-controlling movement on the side of the casing 80 and having a connected part slidably movable therewith for placing the casing in electrical connection with the other terminal of the battery. 85

3. A pocket flashlight comprising a conducting casing having at one end a lamp and containing a battery for the lamp, means for retaining the flashlight on the apparel and closing the circuit comprising a slidable resilient clip on the side of the casing having a 90 connected conducting part, a covering of non-conducting material on the battery for insulating the battery from the casing, and a spring for maintaining the engagement of one of the terminals of the battery with the 95 lamp and engaging the other terminal of the battery, said conducting part being adapted through the sliding of said clip to move into or out of engagement with said spring for making or breaking the circuit of the battery 100 through the lamp. 105

4. A pocket flashlight comprising a conducting casing having at one end a lamp and a removable other end portion and containing a battery in a plural number of end-to-end cells for said lamp, means for retaining the flashlight on the apparel and closing the circuit comprising a slidable resilient clip on the side of said casing and having a connected part movable therewith for placing the 110 casing in electrical connection with the zinc of the inner battery cell, a wrapping of non-conducting material on said cells, and a spring for maintaining the engagement of the outer battery cell with the lamp. 115

5. A pocket flashlight comprising a conducting casing having at one end a lamp and a removable other end portion and containing a battery in a plural number of end-to-end cells for said lamp, means for retaining the flashlight on the apparel of the owner 120 and closing the circuit comprising a slidable resilient clip on the side of said casing having a connected conducting part, a wrapping of non-conducting material on said cells, and 125 130

a spring for maintaining the engagement of the carbon of the outer battery cell with the lamp and engaging the zinc of the inner battery cell, said conducting part on the sliding 5 of said clip being adapted to move into or from engagement with said spring for making and breaking the circuit.

6. In a device of the character described, a metallic casing, a battery mounted therein, 10 a lamp mounted at one end of the casing and electrically connected thereto and to one pole of the battery, means mounted at the other end of the casing and insulated therefrom and electrically connected to the other 15 pole of the battery, a conductor slidably mounted upon and extending within the casing and electrically connected therewith and adapted when operated to contact with said means to complete the circuit through 20 the lamp, and operating means for said conductor comprising a slide provided with means for retaining the device on the apparel.

7. A portable flashlight comprising a casing 25 of conducting material, a battery therein, an electric lamp having one terminal in engagement with one end of said battery and its other terminal in electrical engagement with said casing, a conductor electrically engaged with the other end of said battery and insulated from said casing, a slide on the exterior of said casing, a conducting circuit-closing member within the casing and connected with said slide, whereby on the movement 30 of said slide in one direction said member may be moved into engagement with said conductor to complete the circuit, and means carried by said slide for retaining the flashlight on the apparel, said means comprising 35 a resilient clip projecting from the slide and adapted to receive between itself and the casing the material of the apparel on which the flashlight may be carried.

8. A portable flashlight comprising a metallic casing, a battery therein, an electric lamp having one terminal in engagement with one end of said battery and its other terminal in engagement with said casing, a spring engaging the other end of said battery, 50 a body of insulating material within the casing to which said spring is secured and by which said spring is insulated from the casing, a conductor slidably within the casing longitudinally thereof and electrically connected therewith and adapted when operated to come into contact with said spring to complete the circuit through the lamp, and a slide on the exterior of the side of the casing and slidably longitudinally thereof for operating 55 said slidable conductor.

9. In a flashlight comprising an exterior casing having at one end a lamp and containing a battery for the lamp and a spring at the other end of the casing engaging the

battery, a body of insulating material within 65 the casing through which the outer end of said spring extends, and circuit-closing mechanism comprising a slidable member slidable within said casing longitudinally thereof and having a laterally extending end 70 overlapping a portion of the spring, and an exterior sliding member mounted on the side of the casing to slide longitudinally thereof for manual operation and connected with said inner slidable member.

10. A portable electric light comprising an elongated casing adapted to carry a lamp at one end thereof and to contain a battery for the lamp, and means for controlling the circuit of the battery through the lamp including a circuit-controlling slide mounted on the casing for sliding circuit-controlling movement longitudinally of the casing and provided with a clip forming a hook projecting toward the lamp-carrying end of the 80 casing and adapted releasably to engage a part of the apparel for supporting the light thereon.

11. A portable electric light comprising a battery-containing and lamp-carrying casing, means for controlling the circuit of the battery through the lamp including a circuit-controlling slide mounted on the casing for sliding circuit-controlling movement, and a clip carried by the slide and forming 90 a hook projecting from the slide toward the direction in which the slide moves to close the circuit, whereby when the light is supported by the hook the weight of the light 95 will tend to hold the slide at its open circuit position.

12. A portable electric light comprising an elongated casing adapted to carry a lamp at one end thereof and to contain a battery for the lamp, means for controlling the circuit of the battery through the lamp including a circuit-controlling slide mounted on the casing for sliding circuit-controlling movement longitudinally of the casing and arranged to have movement toward the 105 lamp-carrying end of the casing for closing the circuit, and a clip carried by the slide and forming a hook projecting toward the lamp-carrying end of the casing and adapted releasably to engage a part of the apparel 110 for supporting the light thereon and whereby by reason of such engagement the weight 115 of the light will tend to maintain the slide at the open circuit position.

13. A portable electric light comprising 120 an elongated battery-containing and lamp-carrying casing, a circuit-controlling slide mounted on the casing for sliding circuit-controlling movement longitudinally of the casing, and means carried by the slide for 125 supporting the light and adapted to maintain the slide in a desired circuit-controlling position by reason of the weight of the light,

14. A portable electric light comprising an elongated battery-containing and lamp-carrying casing, a circuit-controlling slide mounted on the casing for sliding circuit-controlling movement longitudinally of the casing, and means carried by the slide for releasably connecting the light with a part

of the apparel and adapted to maintain the slide in a desired circuit-controlling position by reason of the weight of the light.

10

In testimony whereof, I have affixed my signature to this specification.

BERNARD BENEDICT.
